UNITED STATES PATENT OFFICE.

JOHN H. BARR, OF NEW YORK, N. Y., ASSIGNOR TO REMINGTON TYPEWRITER COMPANY,
OF ILION, NEW YORK, A CORPORATION OF NEW YORK.

TYPE-WRITING MACHINE.

1,320,034.

Specification of Letters Patent. Patented Oct. 28, 1919.

Application filed May 21, 1918. Serial No. 235,812.

To all whom it may concern:

Be it known that I, JOHN H. BARR, citizen of the United States, and resident of the borough of Manhattan, city of New York, in 5 the county of New York and State of New York, have invented certain new and useful Improvements in Type-Writing Machines, of which the following is a specification.

My invention relates to typewriting machines and it has for its object to provide 10 certain improvements in said machines.

One of the principal objects of the invention is to provide a typewriting machine that can be collapsed or compacted to make it 15 more convenient for carrying about, and that can be extended or expanded to bring it into position for use.

To the above and other ends my invention consists in certain features of construction and combinations and arrangements of parts, all of which will be fully set forth herein and particularly pointed out in the 20 claims.

A typewriting machine embodying all the 25 features of my present invention is illustrated in the accompanying drawings in which—

Figure 1 is a side elevation of the machine in expanded position ready for operation.

Fig. 2 is a front to rear vertical section in 30 expanded position.

Fig. 3 is a perspective view of a portion of the framework which carries the printing mechanism.

Fig. 4 is a perspective view of a part of 35 the frame which carries the platen and which can be shifted to different case positions.

Fig. 5 is a side elevation of the machine in collapsed or compacted position.

Fig. 6 is a front to rear vertical sectional view taken just to the right of the left-hand shift key of the machine and looking toward the left, the machine being in expanded position.

Fig. 7 is a top plan view of the left-hand 45 half of the machine, in expanded position.

Fig. 8 is a front to rear vertical sectional view of the machine in compacted position.

Fig. 9 is a diagrammatic plan view of the 50 type bar system in its extended or outstanding formation, ready for use.

Fig. 10 is a similar view but showing the set of type bars in its flattened or compacted formation.

55 The frame which supports most of the

mechanism of the typewriter will be most readily understood from Fig. 3 which shows a portion of said frame, the remainder being broken away. The frame comprises right and left-hand end pieces 1 which are connected together at their forward ends by a double comb plate 2, which can be secured to the side plates 1 in any suitable way. As here shown, each of said plates has an ear 3 to which the comb plate 2 is secured by a bolt 60 and nut 4; and the side plates also have lugs or ears 5 which project forward through suitable openings in the comb plate and which may or may not be riveted up on their forward ends. The side plates 1 are 65 connected near their rear ends by a casting designated generally by the numeral 6 and comprising a type bar mount or segment 7 and a sub-lever segment 8, said two segments lying substantially horizontal, the sub-lever 70 segment in front of the type bar segment. Said segments at their ends are integral with a bracket portion 10 of the casting which 75 portion is secured to the side plate 1 by means of an angle-iron 11 whose flanges are 80 secured to the bracket 10 and to the side plate 1 respectively by rivets 12. The end of the bracket 10 does not reach quite to the side plate 1, leaving an opening or slot at the point marked 13 in Fig. 3, which serves 85 as a guide for a movable part of the machine, as will appear hereinafter. A comb plate 14 extends from right to left across the machine, being secured to the under side of the casting 6 by screws 15 (Fig. 2). This 90 comb plate is bent down at its rear edge and is formed with a series of prongs or tines 16 leaving slots 17 between them. The prongs 16 are bent as shown to support a pivot rod 18, alternate prongs being bent toward the 95 front and toward the rear of the machine so as partially to embrace said rod and to support it in place.

The printing key levers 20 of the machine are pivoted on the rod 18 and are guided in 100 the slots 17, and near their forward ends said key levers are guided in slots 21, Fig. 3, in the lower part of the comb plate 2. The key levers 20 carry at their forward ends printing keys 22 arranged as shown in the present instance in four rows. Each of said key levers is connected by a vertical link 23 with a sub-lever 24 of the third order. Said levers 24 are pivoted at their forward ends 105 in slots 25, Fig. 3, in the upper part of the 110

comb plate 2 where they are retained in position by a bar 26 lying across the upper edge of said comb plate and secured in position in any suitable manner, as for example 5 in the manner shown in Fig. 6. Said bar as shown is provided at each of its ends with an ear 27 that hangs down in front of the comb plate 2 and through which the bolt or screw 4 passes:

- 10 Referring to Fig. 2, for example, each of the levers 24 has pivoted in the forward end thereof a link 28 which extends upward therefrom and is pivoted to the forward end of a sub-lever 30, which is one of a series of 15 sub-levers pivoted on a wire 31 in the sub-lever segment 8. Said segment has the general form of an arc of a circle and has cut in its upper part a series of radial guide slots 32 for the several sub-levers 30 and the 20 wire 31 lies in a suitable slot cut in the forward face of the segment 8 where it is secured by two screw nuts 33, Fig. 3, one threaded onto each end of it.

Each of the sub-levers 30 has gear teeth 25 34 on its rear end, which mesh with gear teeth 35 on the heel of the corresponding type bar 36. All of the type bars are guided in radial slots 37 in the type bar segment 7 and they are pivoted on a wire 38 lying in 30 a suitable slot 40 cut in the rear face of said segment, and said wire is secured in position by the flat heads of two screws 41 screwed into the casting 6 and the heads of the screws engaging the ends respectively of the wire. The segment 7 is so shaped that the rear toothed ends of the sub-levers 30 also pass through the slots 37 and are guided thereby, and are thus prevented from getting out of mesh with 35 the gearing on the heels of the type bars.

The disposition and proportions of the sub-levers 24 will be understood from Fig. 7, where it will be seen that all of the sub-levers 30 terminate in an arc convex to the 40 front of the machine and that the links 28 are therefore also disposed in an arc. The levers 24 are therefore made of varying lengths, that shown in Fig. 2 being one of the shortest and the levers increasing in 45 length toward the right and left-hand sides of the system. The links 23 which connect the levers 24 with the key-levers 20, are suitably disposed in a front and back direction so that each one of them gives the 50 proper leverage for its key lever on the sub-lever 30. As said sub-levers 30 are all alike they all have the same extent of oscillation when the keys are depressed.

Each type action is provided with a 55 turning spring 42, said springs in the present instance being connected to the forward ends of the levers 30 and each of them connected also to a hook 43 bent back from the forward edge of a plate 44 which plate 60 overlies the sub-levers 30 and is secured by

screws 45 to the upper part of the segment 8.

The type bars 36 each carry in the present instance two types 46 and said type bars are adapted to swing rearward and downward and to strike against the upper face of a platen 47. The present machine is therefore a top strike machine. Said type bars normally rest against a pad 48, which, when the machine is extended or expanded 75 ready to be used, stands in the position shown in Fig. 2, where, in the present machine, the type bars incline upward and toward the front of the machine. In the present instance these type bars turn through an angle of something like 120° to strike the platen, but this can be varied; and when the machine is compacted, they are moved back to a greater angle from the platen, or an angle of nearly 180°. When the machine is 80 in its expanded position the set of type bars stand up as shown in Figs. 1, 2 and 9; but when the machine is compacted they occupy a low-lying substantially horizontal position, as shown in Figs. 8 and 10, in which 85 position it will be seen they do not project above the machine, and the machine therefore as a whole takes up less space and can be put into a smaller case than it could if the type bars stood up as shown in Fig. 1. 90

The dropping back of the type bars to the position shown in Figs. 8 and 10 and their elevation to the position shown in Fig. 2, are preferably effected by moving the pad 48, and in the present instance said pad is 100 moved for this purpose down and up. But the raising and lowering of the type bars may be effected in a variety of other ways, some of which will be shown in specific applications presently to be filed. The partic- 105

ular mechanism shown for that purpose in the present case will be fully explained hereinafter. Such motion of the type bars is permitted, however, by a peculiarity in the gearing 34, 35 by which said type bars are operatively connected with the sub-levers 30. To this end the heel of each type bar has in front of and above its series of gear teeth 35 a smooth circular convex edge 50 which is adapted to register with a smooth concentric edge portion 51 on the sub-lever 30 above the gear teeth 34. When the type bar is in its elevated position, shown in Fig. 2, in which position it is ready to be operated, the forward one of the teeth 35 lies in the interdental space between the uppermost tooth 34 and the concave edge 51 of the sub-lever. If the pad 48 be depressed the type bar can drop down to the position shown in Fig. 8. In the first part of this motion the uppermost tooth 35 will slightly depress the rear end of the sub-lever 30 by its action on the uppermost tooth 34 and this will slightly elevate the corresponding key lever 20, as will be ob- 110

served by comparing the positions of said key levers in the comb plate 2 in Figs. 2 and 8. After thus slightly depressing the rear end of the lever 30, however, the smooth 5 part 50 of the type bar slides along the concave part 51 of the sub-lever without further operation of said sub-lever, the gear teeth 35 running out of mesh with the gear teeth 34 so that the sub-lever and key are 10 operatively disconnected from the type bar.

By an inspection of Fig. 8 it will be perceived that when the parts are in the collapsed position the co-operation of the concave 51 and the convex edge 50 will be such 15 as to lock the sub-lever 30 and, therefore, the key, against operation. When the type rest 48 is elevated from the Fig. 8 to the Fig. 2 position the reverse of the above cited operations takes place. That is to say, 20 the type bar turns independently of the sub-lever until the first tooth 35 runs into the interdental space just beneath the concave 51, after which said tooth moves the sub-lever back to its Fig. 2 position, where the 25 gearing 34, 35 is again in mesh, when the keys are restored to operative connection with their type bars. It will be perceived that the gearing between the sub-levers 30 and type bars 36 is of the sort known as 30 "intermittent gearing", and it will be so designated in some of the claims.

A good collapsible typewriter can be made merely by the utilization of the principle of the mechanism already described; 35 that is to say, of arranging to change the formation of the type bars from the expanded formation shown in Figs. 1 and 2 to the contracted formation shown in Fig. 8. In the present instance, however, I have provided means for still further contracting 40 the machine, and to this end the frame 1, 2, 6, itself is made movable from an extended position to a contracted position, and other parts of the machine also are 45 extensible and contractible, as will appear from the following description.

The type-action-carrying-frame is supported at its forward part by two links 52 and at its rear part by two links 53, Figs. 50 1 and 5, said links being pivoted to the side plates 1 on pivot screws 54. The links 52 are pivoted at their lower ends at 55 and the links 53 are pivoted at their lower ends at 56 to a stationary base 57 which is provided with rubber feet 58 designed to rest 55 on a desk or table.

The base 57 can be of any appropriate form. As here shown it is approximately in the form of a rectangle and is made of 60 sheet metal having an upstanding rim 60 and a horizontal flange portion 61, the whole construction being such that said base is light in weight and yet sufficiently strong for its purpose. This base can have any 65 suitable side plates attached thereto, such,

for example, as is shown at 62 in Figs. 1, 5 and 8. In Figs. 1 and 5 this plate is removed from the side nearest the observer in order to avoid hiding the mechanism.

The connection of the links 52, 53 with 70 the base 57 and with the frame 1, 2, 6, is such that said frame can be elevated to the position shown in Fig. 1 or be depressed to the position shown in Fig. 5, said links 75 rocking about their pivots in moving from one of these positions to the other. In order to retain the frame in its upper position any suitable means can be provided, that here shown consisting of a pair of flat springs 63 each secured to the flange 61, 80 of the base 57 by screws 64, and said springs inclining upward and toward the rear and each terminating in a loop 65, which when the machine is in its extended position catches under a pin 66 projecting from the 85 link 52. These springs hold the frame in its elevated position with a sufficient degree of security but upon the exertion of enough force the tension of the springs can be overcome and the frame dropped down 90 to the Fig. 5 position.

When the frame is raised to its upper position, shown in Fig. 1, it is arrested by a lug or ear 67 on the front edge of each of the links 52, said lugs striking against 95 a slightly projecting end 68 of the comb plate 2.

Means are provided whereby when the frame 1, 2, etc., is elevated with relation to the base 57 the back stop or cushion 48 for the type bars is at the same time raised still higher so that it not only partakes of the upward motion of the frame 1, etc., but moves upward still farther and with relation to said frame 1 so as to elevate the type 100 bars to their extended position. This can be effected by a variety of means and the particular means shown in the drawings will now be described. Each of the links 52 and 53 has an arm 70, which arms, when 105 the parts are in the Fig. 1 position, extend upward and forward from the pivot screws 54; and at their upper or forward ends said arms 70 are by pivot screws 71 pivoted to side plates 72, there being one of 110 these plates on each side of the machine, and said plates extending upward from the pivots 71 as shown in Fig. 1, for example. It will be perceived that the location of the pivots 71 with respect to the pivots 55, 115 56 differ from the location of the pivots 54 in two particulars; that is to say, said pivots 71 are both farther from the pivots 55, 56 and they are also in a different direction from said pivots than the pivots 54, 120 so that the motion of the plate 72 is somewhat different from the motion of the plate 1. That is to say, the plate 72 moves up and down farther than the plate 1 and its motion is also somewhat more nearly 130

straight up and down—it has not quite so great a component of motion in the horizontal direction as the plate 1.

A top plate 73 is secured by screws 74 to 5 the upper parts of the two plates 72. From an inspection of Figs. 2, 7 and 8 it will be perceived that the rear and middle part of the said top plate is depressed below the upper edges of the side plates 1, the line of 10 depression being indicated at 75 in Figs. 2 and 7. This depression forms a sort of semi-circular pan in which the type bars lie when the machine is in its compacted position as shown in Fig. 8. The type rest 48 consists 15 of a piece of some suitable material, such, for example, as felt or leather, lying in an arc-shaped channel 76 in the rear edge of the top plate 73. The top plate, of course, partakes of the up and down motion of the 20 side plates 72 and as this up and down motion exceeds the up and down motion of the frame 1, 2, etc., in which the type bars are mounted, it will be perceived that in collapsing and extending the machine said type 25 rest 48 moves up and down relatively to the type bar segment 7 and raises the type bars in the one instance to the position shown in Fig. 2 and in the other instance allows them to drop down to the position shown in Fig. 8.

30 It will be perceived that the machine has at one operation a double expansion and contraction in an up and down direction; that is to say, the whole type action frame is dropped down into the base plate 57 which 35 has the form of a sort of pan and at the same time the type bars drop down into compact relation with the balance of the type action.

It will also be perceived that the motion 40 of the parts is such that the machine is expanded and contracted lengthwise as well as up and down. When the machine is in its extended position shown in Fig. 1, the platen 47 and the carriage and associated 45 parts stand out some distance behind the rear edge of the base 57, but when the machine is contracted to the Fig. 5 position these parts come inside of said base. This fore-and-aft contraction of the machine is, 50 of course, due to the swinging of the upper ends of the links 52, 53, not only downward but also toward the front of the machine. Said links, when in expanded position, stand approximately vertical, whereas, when in 55 compacted position, they lie toward the front of the machine, more nearly horizontal. When the machine is in its compacted position, it can be expanded by the operator grasping the projecting edges of the top 60 plate 73 and raising said top plate to its expanded position. All of the other parts, including the type bars, automatically assume their expanded positions also, at the same time, so that the machine can be brought 65 into condition for use by this single motion.

The machine is equipped with a space bar 77 which when said machine is in its extended position stands in its usual relation to the printing keys, that is to say, forward of 70 and somewhat lower than the first row of said keys, as shown in Fig. 1. But when the machine is in its compacted position, shown in Fig. 5, said space bar is underneath the forward row of keys. By comparing Figs. 1 and 5 it will be perceived that the 75 actual motion of the space bar has been somewhat similar to that of the other parts; that is to say, in compacting the machine said space bar has moved forward and downward, but it has not moved as far forward as the printing keys 22. It will also be perceived that this peculiarity of the motion of the space bar has the effect of a contraction of the machine in a front and rear direction. Such motion is brought about by 80 the peculiar mounting of said space bar which is here shown as a bar of any suitable material secured by screws 78, Fig. 1, to the front cross bar 80 of a yoke-shaped frame, which comprises side bars or lever arms 81, 90 one at the right-hand and the other at the left-hand side of the machine, said levers 81 being pivoted at their rear ends on pivot screws 82 threaded into the links 53 at points approximately midway between the 95 pivots 54, 56 but as here shown slightly nearer to the front of the machine than the pivot 54. When the machine is in its extended position ready for use, these screws 100 82 serve as suitable fulcrums for the space frame, but when the machine is compacted the pivot screws 82, by reason of their peculiar relation to the pivots 56 obviously do not move as far toward the front of the machine as the screws 54 and this accounts for 105 the space bar having a forward motion less than that of the printing keys 22.

In order to pivot the spacing levers 81 to the links 53 in the manner described it has been found convenient in the present instance to make these levers of a peculiar form. It will be noted in Fig. 7 that the forward end of the lever 81 there shown lies to the right of the shift key lever and it will be noted from Fig. 1 that the rear end of 110 the lever 81 there shown, this being the right-hand one, however, is pivoted to the outside of the link 53; and it will be perceived that this involves off-setting the rear part of each lever 81 from the front part. 115 This off-setting is effected chiefly by cutting out the lever 81 in the first place of a form that will be understood from the following description and making two bends in it, the front part of the lever and the rear part 120 being connected by a horizontal flat part 83, Figs 1 and 7, this flat part of the lever underlying the shift key lever. The off-setting is added to by a slight bending of the rear 125 part of the lever which bending, however, 130

it has not been thought necessary to show in the present drawing. The levers 81 of the space bar are provided with any suitable restoring springs 79 (Fig. 2).

- 5 The carriage 84 of the machine can be of any suitable kind as far as my present invention is concerned. As here shown it comprises a bed-part bent at its front and rear edges to form two ball-bearing rails 85 which face two relatively stationary grooved rails 86. Standards 87 rise from the bed 84 of the carriage and support the platen 47. Said carriage and platen may be equipped with any suitable paper feed devices 88 and 10 the carriage is shown as propelled by a spring-motor 90, which in the present instance is mounted on the carriage itself and is connected by a strap 91 with a stationary bracket 92.
- 15 20 The case shift mechanism has features of novelty about it and it includes means for shifting the entire carriage and its stationary rails 86 in a front and back direction and also shifting the ribbon and escapement 25 mechanisms, including the universal bar. The rails 86 are mounted on horizontal brackets or arms 93 from one of which the bracket 92 projects, said rails being fastened to the brackets 93 by screws which pass 30 through holes 94, Fig. 4. Said Fig. 4 shows the left-hand one of the two side pieces which together with the rails 86 constitute the main part of the shift frame. Each of 35 said side pieces consists of a vertical plate 95 made of sheet metal and having the bracket 93 bent off from the rear part of the lower edge thereof.

40 The vertical part of the plate 95 lies against the inside face of the side plate 1 of the type action frame, a portion of the straight upper edge thereof lying in the slot 13, Fig. 3, between the end of the casting 6 and the side plate 1, which slot therefore serves in part as a guide for the shift frame. 45 The plate 95 is supported in the manner shown in Fig. 6. Said plate is prolonged toward the front of the machine as shown in Fig. 4 and at its forward end has a pivot pin 96 projecting therefrom, which pin is 50 pivoted in the lower end of an arm 97 fixed on a transverse rock shaft 98 extending across the front of the type bar frame, said shaft being pivoted to said frame on a pivot screw 100, Fig. 7, screwed through a hole 55 101, Fig. 3, in an upstanding ear of the side plate 1. As this rock shaft extends across the machine and is connected with the plates 95 on both sides of the machine it insures that the two ends of the shift frame shall 60 move front and back to the same extent.

65 Each of the plates 95 is, near its rear end, pivoted at 102 to the lower end of a link 103 which is pivoted at 104 to the side plate 1. the links 103 being substantially parallel to the arms 97, so that the shift frame has sub-

stantially a horizontal front and back motion. It will be perceived that this shift frame is swung from the type action frame so that it and the carriage and platen, as well as the escapement and ribbon mechanisms, are movable up and down with said type action frame in the act of extending and contracting the machine.

70 The shift key 105 and its connections are shown in Figs. 6 and 7. Said key is mounted on the forward end of a key lever 106 which at its rear end is pivoted on the same rod or wire 18 as the printing key levers. A link 107 is connected at its lower end to the key lever 106 and at its upper end said link is pivoted at 108 to a bell crank 110 which is pivoted on a pivot screw 111 screwed into an ear 112 of the side plate 1. The bell crank 110 is folded upon itself so as to take a bearing on the screw 111 at two 85 points spaced apart, and the depending arm of said bell crank has a slot 113 in which plays a pin 114 on the left-hand side piece 95 of the shift frame. The construction is such that when the key 105 is depressed said shift frame is pushed toward the rear of the machine. Said shift frame is normally held in its forward position by means of a returning spring 115 which is connected at its 90 forward end with the bell crank 110 and at 95 its rear end to the link 103.

95 The stops for limiting the front and rear movements of the shift frame consist of pins 116 projecting eccentrically from the ends of screws 117 threaded through the side plates 100 1 and having outside of said side plates lock nuts 118, Fig. 1. An upstanding lug 120 on the side piece 95 on each side of the machine, is adapted to play between a pair of the stop pins 116, said lug being arrested by said 105 pins. It will be perceived that the precise position of each pin 116 can be regulated by giving a part turn to its screw 117 and securing the screw in its adjusted position by tightening the lock nut 118.

110 The carriage escapement mechanism including the universal bar is carried by the shift frame and consequently these parts move up and down when the machine is extended or compacted and they also shift 115 front and back when the platen is shifted. A feed rack 121 is mounted on the carriage 120 84 by means of brackets 122 secured to said carriage by screws 123, said rack lying horizontally in front of the carriage and facing upward. Coöoperating with said rack are any suitable feed dogs 124 mounted on the end of an arm 125 loose on and projecting downward from a transverse rock shaft 126, which at its ends is pivoted on pivot screws 127, Fig. 7, passing through ears 128 at the upper rear parts of the side plates 95 of the shift frame. The arm 125 is one arm of an angled lever having another arm 130 projecting forward from the shaft 126 and hav- 130

ing a pin 131 at its free end, said pin projecting into a hole 132 in an arm 133 which is fixed to the shaft 126 near the middle of the machine. The hole 132 is larger than 5 the pin 131 so as to provide lost motion between the shaft 126 and the arms 130 and 125, whereby the extent of oscillation of the arm 125 is less than that of the shaft 126.

Said shaft 126 is operated through the 10 instrumentality of two arms 134 which extend from said shaft forward and downward, there being one of said arms at each end of the shaft just inside the plate 95. Each of the arms 134 is forked at its forward end to embrace a pin 135 projecting from the end of a lever 136 pivoted at 137 to the lower part of the plate 95 of the shift frame. Each lever 136 has a second arm 138 extending toward the front of the machine from the pivot 137 and a universal bar 140 is mounted on the forward ends of the two levers 138. Each of the levers 138 has a bracket or ear 139 bent off therefrom a little forward of the pivot 137 and said 25 brackets underlie the space key levers 81 as best shown in Fig. 1. As these two levers are pivoted on the shift frame it will be seen that they move front and back with said shift frame. The universal bar is here 30 shown as a round rod suitably mounted on the free ends of the levers 138 and lying beneath lugs 141 formed on the lower sides of the printing key levers 20, said lugs being of such length that they overlie the universal bar in both of its case shift positions. Restoring springs 142 for the universal bar are here shown as plate springs secured at 35 their rear ends to the bracket 93 of the shift frame and at their forward ends underlying the arms 138.

The ribbons spools and their driving mechanism are also mounted on the shift frame so that said spools are maintained in the same relation to the platen in both shifted positions of said platen. As shown in 45 Fig. 4 a bracket 143 is bent horizontally toward the middle of the machine from the rear part of the upper edge of the shifting plate 95 and said bracket has a hole 144 therein in which is mounted the stud 145, Fig. 7, of the ribbon spool 146, this same construction being, of course, duplicated on the two sides of the machine. As best shown in Fig. 4 the inner end of the 50 bracket 143 is bent up to form an ear 147 having a notch 148 therein in which notch is journaled one end of a drive shaft 150 having thereon at each end thereof a bevel pinion 151 adapted to mesh with a bevel or 55 crown gear 152 secured to the lower flange of the ribbon spool 146. In the machine represented in the drawings, means are provided for shifting the shaft 150 endwise to cause it to drive the right or lefthand spool as required. Said means is not shown in 60

the present drawings, however, because the details of the ribbon mechanism form no part of the present invention except in their relation to the case shift frame on which said mechanism is mounted. The shaft 150 70 can be driven in any suitable way. It is here shown equipped with a ratchet wheel 153 which can be operated by any suitable pawl mechanism from the shaft 126 which, it will be recalled, is operated by the universal bar.

The machine can be provided with any suitable form of ribbon vibrator, that here shown comprising a plate or bar 154 of sheet metal lying beneath a rigid bracket 80 155 projecting rearward at an upward inclination and secured at its forward end by a screw 156 to the rear face of the type bar segment 7 at the middle of the machine. This bracket 155 has ears 157 at its forward 85 end serving as a center guide for the type bars. The ribbon vibrator bar 154 has ears 158 overlapping the bar or type guide 155 and it also has ears 160, Fig. 7, projecting from one side thereof, one in front of and 90 the other behind the upper end of the lever arm 133 which is mounted on the universal rock shaft 126. The vibrator bar 154 has any suitable loops or ribbon guides 161. It will be perceived that the vibrator is moved 95 back and forth with the strokes of the printing keys after the usual fashion of such devices, and that it partakes of the entire rocking motion of the shaft 126 of which the feed dogs 124 partake of only a part, due 100 to the lost motion connection 131, 132. It will also be understood that the ribbon vibrator slides along the bar 155 when the case shift key is operated.

The drawings show a bail-shaped frame 105 or bracket 162 secured at its lower end to the under side of one of the rails 86 and lying just in front of the platen 47. This bail or bracket has certain paper controlling devices connected therewith but these 110 constitute no part of the present invention.

It will be noted that the type bars are independently operable or independently movable about their pivots and that when the machine is in its extended position said 115 type bars are arranged in the formation or relative disposition shown in Figs. 1, 7 and 9, whereas when the machine is compacted or collapsed this formation or relative disposition of the type bars is changed into the 120 one indicated in Figs. 8 and 10. It will be recognized that this change in the formation of the set of type bars is a thing distinct from the movement of the set of type bars as a whole due to the movement up and 125 down of the type bar segment or common support 7.

Various changes can be made in the details of construction and arrangement without departing from my invention.

What I claim as new and desire to secure by Letters Patent, is:—

1. In a typewriting machine, a set of individually operable type bars, said type bars movable relatively to each other into two different formations, in one of which said type bars are ready to be operated, and the other of which formations renders the machine, as a whole, more compact. 5
2. In a typewriting machine, a set of individually pivoted type bars which can be moved about their pivots into two different formations, in one of which said type bars are ready to be operated, and the other of which renders the machine, as a whole, more compact. 10
3. In a typewriting machine, the combination of a type bar segment, a series of type bars pivotally mounted upon said segment, and means for moving said type bars about their pivots from a flattened formation into an outstanding formation. 15
4. In a typewriting machine, the combination of a set of individually operable type bars, means for moving said type bars lying in flattened formation relatively to each other into an outstanding formation, and printing keys and connections capable of operating said type bars when disposed in said outstanding formation. 20
5. The combination of a set of individually operable type bars, and a type bar rest movable into two positions, in one of which said rest holds said type bars in a formation where they are ready for operation, and said rest when moved to the other of said positions allowing said type bars to move into a compacted formation. 25
6. The combination of a set of type bars pivoted in an arc, and a type bar rest movable toward and from the plane of said arc, said rest in one position holding said type bars in a formation where they are ready to be operated, and said rest movable to another position allowing said type bars to swing about their respective pivots into a compacted formation and means capable of operating said type bars when they stand in the first mentioned formation. 30
7. The combination of a frame, a set of key levers, and a set of type bars both mounted in said frame, and a type bar rest shiftable relative to said frame to change the formation of said set of type bars. 35
8. In a typewriting machine, the combination of a set of type bars, keys and connections for operating said type bars, and means whereby the operator of the machine can compact said machine, said compacting means including means for breaking the operative connections between the keys and their respective type bars and for moving said type bars relatively to their mount and to one another to compacted position. 40
9. In a typewriting machine, the combination of a set of pivoted type bars, keys and connections for operating said type bars, and means whereby the operator of the machine can move said type bars about their pivots into a compacted formation, the last recited means including means for breaking the operative connections between the keys and the type bars. 45
10. In a typewriting machine, the combination of a set of pivoted type bars, keys and connections for operating said type bars, and means whereby the operator of the machine can cause said type bars to swing about their pivots into a flattened formation breaking the operative connections between said keys and type bars. 50
11. In a typewriting machine, the combination of a set of type bars, keys and connections for operating said type bars, means whereby the operator of the machine can move said type bars about their pivots into a compacted formation, said means including means for locking said keys against operation. 55
12. In a typewriting machine, the combination of a set of type bars, keys and connections for operating said type bars, means whereby the operator of the machine can move said type bars about their pivots into a compacted formation, said means including means for breaking the operative connections from said keys to said type bars and for locking said keys against operation. 60
13. In a typewriting machine, the combination of a set of type bars, keys and connections for operating said type bars, and means whereby the operator of the machine can move said type bars in directions opposite of those in which said type bars are operated by said keys into a compacted formation. 65
14. In a typewriting machine, the combination of a set of type bars, keys and connections for operating said type bars, and means whereby the operator of the machine can move said type bars in directions opposite of those in which said type bars are operated by said keys into a compacted formation, said type bars in such opposite movements moving out of operative connection with said keys. 70
15. In a typewriting machine, including printing keys, means for compacting the machine when not in use, and means for at the same time locking said keys against operation. 75
16. In a typewriting machine, the combination of a type bar, a key, and connections from said key to said type bar, said connections including intermittent gearing. 80
17. In a typewriting machine, the combination of a type bar, a key, and connections from said key to said type bar including a sub-lever geared to said type bar by intermittent gearing. 85

18. In a typewriting machine, the combination of a type bar, a key, connections from said key to said type bar including intermittent gearing, and means for holding said type bar normally in one position where said gearing constitutes an effective operating connection from the key to the type bar and for moving said type bar to another position where the smooth part of the intermittent gearing is in engagement.
19. In a typewriting machine, the combination of a type bar, a key, connections from said key to said type bar including a segment, intermittent gearing between said segment and the heel of the type bar, and means for normally holding said type bar in a position where the toothed part of the intermittent gearing is in mesh and for allowing said type bar to drop back to compacted position where the smooth part of the intermittent gearing is in engagement, such smooth part of said intermittent gearing in said compacted position serving to lock the key against operation.
20. In a collapsible typewriting machine, the combination of a frame comprising a base part and a second part extensible and collapsible relative to said base part; keys, type mechanism and a paper carriage mounted in said second part; and a parallel linkage system connecting the two said frame parts.
21. In a collapsible typewriting machine, the combination of a frame comprising a base part and a second part extensible and collapsible relative to said base part; keys, type mechanism, a platen and case shift mechanism mounted in said second part; and a parallel linkage system connecting the two said frame parts.
22. In a collapsible typewriting machine, the combination of a frame comprising a base part and a second part extensible and collapsible relative to said base part; keys and type mechanism mounted in said second part, a parallel linkage system connecting the two said frame parts, and means for extending and collapsing said type mechanism relative to said second part of the frame when the latter is extended and collapsed relative to said base part.
23. In a collapsible typewriting machine, the combination of a frame comprising a base part and a second part extensible and collapsible relative to said base part, printing keys and a set of type bars mounted in said second part of the frame, and means for changing the formation of said set of type bars to one formation ready for operation when said frame is extended and to a compacted formation when said frame is collapsed.
24. A collapsible frame for typewriting machines comprising in combination a base part, a middle part, and an upper part, and links connecting the three said parts, said middle part being connected with said links between the points of connection of said upper and base parts, whereby, when the frame is collapsed and extended, the upper part moves farther than the middle part.
25. A collapsible frame for typewriting machines comprising in combination a base part, a middle part, and an upper part, and links connecting the three said parts, said middle part being connected with said links between the points of connection of said upper and base parts, whereby, when the frame is collapsed and extended, the upper part moves farther than the middle part.
26. In a collapsible typewriting machine, the combination of a system of parallel links and various parts of the machine pivoted to said links at different points along said links, the machine being collapsible and extensible by the swinging of said links and different parts of the machine having different motions during the collapsing and extending movements depending on their several points of connection with said links.
27. A collapsible frame for typewriting machines comprising in combination a base part, a middle part, and an upper part, and links connecting the three said parts, said middle part being connected with said links between the points of connection of said upper and base parts, whereby when the frame is collapsed and extended the upper part moves farther than the middle part.
28. A collapsible frame for typewriting machines comprising a base part and a collapsible part connected with said base part by a system of parallel links which when in extended position stand approximately vertically and when in collapsed position lie more nearly horizontally whereby the collapsing motion of the frame has both a vertical and a horizontal component so that when collapsed the machine is reduced both in height and in length.
29. In a collapsible typewriting machine, the combination of a frame comprising a base part and a collapsible part, and pivoted links connecting said parts, keys mounted in said collapsible part and a space bar pivoted to said links between their ends whereby when the machine is collapsed the space bar moves a less distance than the keys and is thereby brought into a compacted relation to said keys.
30. In a collapsible typewriting machine, the combination of a frame comprising a base part, a middle part, and a top plate part, and connections between the three said parts allowing said middle part to be extended and collapsed relative to said base part.

and allowing said top plate to be moved into extended and compacted relation to said middle part; type bars mounted in said middle part; and a type rest connected with 5 said top plate, said type rest when the machine is extended holding said type bars in a formation where they are ready for operation and said type rest when in compacted position allowing said type bars to drop 10 back into a compacted formation.

31. In a collapsible typewriting machine, the combination of a frame having a set of type bars mounted therein, a top plate movable into extended and compacted relation 15 to said frame, and a type rest connected with said top plate and acting when said top plate is in extended relation to hold said type bars in an extended formation where they are ready for operation, and when said top plate 20 is in compacted relation allowing said type bars to drop back into a compacted formation.

32. In a collapsible typewriting machine, the combination of a frame having a set of type bars mounted therein, a top plate, a type rest connected with said top plate, and means for effecting a relative movement between said top plate and frame into extended and compacted relative positions.

33. In a collapsible typewriting machine, the combination of a top plate having a depressed part, a set of type bars and a type rest movable into one position where it holds said type bars in an outstanding relation to 35 said top plate, and into another position where said type bars drop back into said depressed portion of the top plate.

34. In a typewriting machine, the combination of a set of type bars capable of 40 occupying as a set a position of use and also a position of disuse, a mount for said type bars, and means whereby said set of type bars may be moved relatively to said mount from the position of disuse to the position of 45 use and vice versa.

35. In a typewriting machine, the combination of a set of pivoted type bars movable all at once about their pivots to two different positions, so that at one time said 50 type bars have an upstanding position and at another time a substantially horizontal position.

36. In a typewriting machine, the combi-

nation of a set of pivoted type bars which when in disuse occupies a substantially horizontal position, and means for raising said set of type bars about their pivots from the last mentioned position to an upstanding position for use. 55

37. In a typewriting machine, the combination of a platen, a set of pivoted type bars which when in printing position stand at a predetermined angle from the printing point and which when in non-printing or collapsed position rest at a greater angle from said 60 printing point. 65

38. In a typewriting machine, the combination with a platen, of a set of type bars capable of lying in an inoperative or collapsed position, a mount for said type bars, 70 and means arranged beneath said type bars for moving them all from said position to an operative position.

39. In a typewriting machine, the combination of a set of pivotally mounted type 75 bars capable of swinging on their pivots from a collapsed inoperative position to an extended operative position and vice versa, and means for further operating said type bars about their pivots for printing purposes 80 when said type bars are in their operative position.

40. In a typewriting machine, the combination of a platen, a set of type bars, means for operating said type bars, said type 85 bars being adapted to swing about their pivots from an operative to an inoperative position, and said means for operating said type bars being incapable of operating said bars when they have been swung to their inoperative position. 90

41. In a typewriting machine, the combination of a platen, a set of type bars which when the machine is in disuse is adapted to occupy a low-down position, and means 95 for moving said type bars to an operative position nearer said platen and maintaining them there during the use of the machine for printing.

Signed at New York, in the county of New 100 York and State of New York this 18th day of May, A. D. 1918.

JOHN H. BARR.
